UNITED STATES PATENT OFFICE.

OTTO BOETTCHER, OF CHARLOTTENBURG, GERMANY.

ACETYLENE-GAS GENERATOR.

SPECIFICATION forming part of Letters Patent No. 634,869, dated October 17, 1899.

Application filed June 19, 1899. Serial No. 721,089. (No model.)

To all whom it may concern:

Be it known that I, OTTO BOETTCHER, a subject of the Emperor of Germany, residing at Charlottenburg, near Berlin, Empire of Germany, have invented certain new and useful Improvements in Acetylene-Gas Generators, of which the following is a full, clear, and exact description.

The present invention relates to acetylene-gas generators; and its object is to dispense with the gasometer and bell, as also with the gas-outlet cock at the apparatus, the quantity of gas generated being dependent on the amount required, and when the generation is to cease the supply of water to the calcium carbide is cut off and the flames allowed to burn out the small quantity of gas left in the carbide-holder.

In order to render the present specification more easily intelligible, reference is had to the accompanying drawing, which shows a vertical section through an apparatus constructed according to the present invention.

The carbide-holder *b* is adjustably suspended in the water-receptacle *c* by means of the gas-outlet pipe *a*. A sleeve *e*, having external threads, is adapted to screw in a bushing in the carbide-holder cover, in which the said sleeve may be adjusted vertically by means of a hand-wheel *f'* or other suitable device. The sleeve *e* is slotted vertically at the top and may be clamped to the pipe *a* by means of a nut *f*. The pipe *a* is fitted gas-tight to the cover *g* of the carbide-holder *b*. To the bottom of the receptacle *b* a housing *h* for a double valve is fixed, said housing projecting inwardly and having an upper conically-formed end with a tapering opening *m* therethrough. The lower part of the housing is provided with a valve-seating *k*, against which a valve *l* is adapted to close under circumstances hereinafter set forth. The valve *l* has a downwardly-extending stem *d*, adapted to contact with the bottom of the water-receptacle when the carbide-holder is lowered. The valve *l* has, further, an upwardly-projecting stem *i*, having a conical top adapted to fit into and close or partially close the throughway *m*. The valve is spring-pressed down onto its seat *k*, so as to close the water-inlet.

The device operates in the following manner: When the apparatus is not in use, the

carbide-holder is in its raised position and the stem of the valve *l* is above the bottom of the water-receptacle, so that the water-inlet valve at *k* is closed. When it is desired to generate acetylene gas, the carbide-holder *b* is lowered a certain distance, according to the number of flames required to burn, and the valve *l* will be slightly opened, so that a very fine jet of water will be able to pass to the carbide in the holder through *m* and gas will be generated, passing along the pipe to the points of consumption. If too much gas is being generated for the number of flames, the holder may be lowered slightly farther, when the conical end of the valve *i* will be inserted into the opening *m* and regulate the water-inlet. The pointed regulating-valve *i* also serves to clean the opening *m* should it get stopped up from any cause. It will thus be seen that the pressure of the gas and the quantity generated will be regulated by the height of the water column in the water-receptacle. If the pressure of gas inside the holder exceeds the pressure of the water column, no more water will for the time being enter the opening *m*, and thus the gas regulates itself automatically. If the supply is to be cut off, the carbide-holder is simply raised and the valve *l* closes under the action of its spring.

If the carbide-holder is taken out for refilling, the valve *l* of the same will also be closed, as will be obvious.

I claim as my invention—

1. In an acetylene-gas generator the combination of a water-receptacle and a carbide-holder having gas-outlet and being vertically adjustably suspended therein a water-inlet valve arranged at the bottom of the said carbide-holder and means in connection therewith for regulating the opening of the said valve by the adjustment of the vertical position of the carbide-holder in the manner and for the purpose substantially as described. 85

2. In an acetylene-gas generator, the combination of a water-receptacle and a carbide-holder having gas-outlet pipe and being suspended therein and vertically adjustable, a water-inlet valve at the bottom of the said holder and a valve-housing to conduct the water to the top of the carbide in the holder, and means in connection with said valve to open and regulate the inlet-opening when the 90 100

holder is lowered and to close the said valve entirely when the holder is raised in the manner and for the purpose substantially as described.

5 3. In an acetylene-gas generator, the combination of a water-receptacle and a carbid-holder having gas-outlet pipe and being adjustably suspended therein, a valve in the bottom of said carbid-holder, having inwardly-extending housing, with upwardly-tapering inlet-orifice at the top and a valve-seat at the bottom, a valve to close onto said lower seat and having upwardly-extending tapered end to fit into and through said tapered opening, and a downwardly-extending stem to contact with the bottom of the water-receptacle in the manner and for the purpose substantially as described.

4. In an acetylene-gas generator the combination of a water-receptacle having therein 20 a carbid-holder with an outlet-pipe and means in connection with said pipe to adjust the holder vertically in the water-receptacle, a valve at the bottom of the said holder and means in connection therewith for regulating 25 the water-inlet according to the position of the holder in the water-receptacle and for closing the valve entirely when the holder is raised or removed in the manner and for the purpose substantially as described.

In witness whereof I have hereunto set my hand in presence of two witnesses.

OTTO BOETTCHER.
